[57] ABSTRACT

An antenna bracket comprising an angled member of insulating material having first and second legs. The first leg has a channel which is adapted to mate with a portion of a support member, and the second leg has at least one bore adapted to receive an end of an antenna element. A terminal assembly is provided within a chamber in the second leg and is adapted to have the ends of the antenna element and of a lead-in wire electrically connected thereto. A fan dipole antenna assembly is also disclosed.

ANTENNA BRACKET

FIELD OF THE INVENTION

This invention relates to an antenna bracket and more particularly to a new and improved antenna bracket for supporting the dipole elements of a fan dipole assembly.

BACKGROUND OF THE INVENTION

In general, outdoor antennas have comprised antenna elements and support brackets which are of exposed metallic construction and are accordingly susceptible to corrosion and oxidation due to adverse weather effects and due to environmental pollution such as smog, soot, smoke and salts. Such ambient conditions have adversely affected both the quality of the signal received and also the structural strength of the antenna. In addition, electrical connections between the driven elements and lead-in wire have generally been exposed to such adverse weather effects and other ambient conditions which has resulted in undesirable detuning and poor signal reception. Such antennas have thus required frequent maintenance and replacement of antenna components and lead-in wires. Many outdoor antennas have also been difficult to assemble and disassemble thus increasing the time necessary to erect the antenna and to maintain it once it is erected.

OBJECT OF THE INVENTION

It is thus an object of the present invention to provide an antenna bracket for an outdoor antenna which is resistant to corrosion and oxidation caused by adverse weather effects and environmental pollution.

It is another object of the present invention to provide an antenna bracket for supporting the driven elements of an antenna in which electrical connections between the elements and a lead-in wire are unexposed to the surrounding environment.

It is a further object of the present invention to provide an antenna bracket which is substantially maintenance-free over a long period of time and which may be quickly assembled into an antenna assembly.

It is yet another object of the present invention to provide a new and improved fan dipole antenna assembly.

SUMMARY OF THE INVENTION

In general, these and other objects and advantages are achieved according to the present invention wherein an antenna bracket is provided comprising an angled member of insulating material having first and second legs. According to an aspect of the invention, the first leg is provided with a channel in a face thereof which is adapted to receive a portion of a support member to which the bracket is to be secured and the second leg is provided with at least one bore adapted to receive the end of an antenna element. The second leg is also provided with a chamber in communication with the bore having a terminal assembly of conductive material positioned therein to which the end of the antenna element is adapted to be electrically connected.

According to a further aspect of the invention another bore is provided in the said second leg for receiving the end of a lead-in wire which is also electrically connected to the terminal assembly. Preferably, the terminal assembly comprises a plate, a screw projecting substantially perpendicularly from the plate, and a pair

of nuts threaded on the plate between which the end of the lead-in wire is trapped to terminate it to said assembly.

According to another aspect of the invention the second leg comprises a first segment integral with the first leg and a second separable segment adapted to be mated with and secured to the first segment. In this aspect of the invention the bores in the second leg are comprised of complementary channels in opposing faces of said first and second segments of said second leg. Preferably, a water tight seal is effected by cementing said first and second segments together to form said second leg and by cementing said antenna elements within said bores.

According to yet another aspect of the present invention dipole elements are supported in the bores of said bracket to form a dipole antenna assembly. Preferably, said dipole elements are cemented within said bores to provide a water tight seal therefor.

DESCRIPTION OF THE DRAWINGS

FIG. 1 is a perspective view of an antenna with a fan dipole utilizing a preferred embodiment of antenna bracket according to the present invention.

FIG. 2 is a partially sectional, plan view of the fan dipole of the antenna of FIG. 1.

FIG. 3 is an exploded view of the fan dipole of FIG. 2.

FIG. 4 is an exploded view of the embodiment of antenna bracket used in the fan dipole of FIG. 1 - 3.

FIG. 5 is a partially sectional elevational view of the bracket of FIG. 4.

DESCRIPTION OF THE PREFERRED EMBODIMENT

Referring now to FIG. 1 there is shown a receiving antenna having a fan dipole assembly provided with a pair of antenna brackets according to a preferred embodiment of the present invention. As shown, receiving antenna 10 comprises a boom 12 secured to a mast 14 by bracket assembly 16. Boom 12 supports a plurality of parasitic antenna elements such as reflector elements 18 and director elements 20. Also secured to boom 12 is a driven fan dipole assembly 22 which in conjunction with parasitic elements 18 and 20 provides FM and TV signal reception.

Fan dipole assembly 22 generally comprises a plurality of dipole antenna elements 24 supported by antenna brackets 26 secured to boom 12.

Referring more particularly to FIGS. 2 and 3 it is seen that brackets 26 are secured to boom 12 and the entire boom and dipole assembly are secured by mast 14 by means of bolts 28 passed through holes 30 in brackets 26, holes 32 in boom 12, holes 34 in mast brackets 36 of assembly 16 and through washers 38 and 40 and nuts 42 threaded on the ends of bolts 28. Brackets 36 are provided with ribs 37 for non-slip gripping of mast 14.

Referring now to FIGS. 4 and 5 there is shown in greater detail a preferred embodiment of the antenna bracket of the present invention. As shown, bracket 26 comprises an angled member 43 having a first leg 44 and a second leg 46. Leg 44 is provided with a channel 48 on its upper surface which is adapted to receive a portion of boom 12 to which bracket 26 is secured. Channel 48 has a configuration substantially complementary to the configuration of boom 12 to insure proper mating of bracket 26 thereto. Since boom 12 is

substantially cylindrical in the illustrated embodiment, channel 48 is also made substantially semi-cylindrical so that when a pair of brackets 26 are secured to boom 12, they substantially enclose boom 12.

Leg 46 is preferably flared at its distal end and is comprised of a first segment 49 integral with leg 44 and a second separable segment 50. Segments 49 and 50 are respectively provided with complementary channels 52 and 54 in opposing faces thereof to form bores when segments 49 and 50 are mated together, said bores being adapted to receive the ends of dipole elements 24. Members 49 and 50 are also respectively provided with complementary channels 56 and 58 for the reception of the end of a lead-in wire 60.

A chamber or recess in leg 46 is formed from recess 62 in segment 49 and aperture 64 in segment 50. A terminal assembly 66 of conductive material is positioned in the chamber comprising recess 62 and aperture 64 and comprises an electrically conductive plate 68, screw 70 projecting substantially perpendicularly to plate 68, and nuts 72 threaded on screw 70. Nuts 72 are adapted to trap the end of conductor 74 of wire lead 60 therebetween to electrically connect lead-in wire 60 to assembly 66.

Dipole elements 24 are also electrically connected to terminal assembly 66 as by soldering the conductors 75 thereof to plate 68. Dipole elements 24 are preferably formed of coaxial cable 75 sheathed in fiberglass 93 in a known manner. In such case the outer conductors of the coaxial cable would be soldered to plate 68.

It will be understood that dipole elements 24 may be made of conductors other than coaxial cable as, for example, solid or tubular elongated members of conductive material sheathed in fiberglass or other insulating material. It will also be understood that dipole elements 24 may be terminated to assembly 66 in any known manner such as by brazing, spot welding or the like.

Aperture 64 in leg 50 is provided with an enlarged portion 76 at the top thereof forming ledge 78 in segment 50. A cover plate 80 of insulating material is adapted to be seated on a ledge 80 in enlarged portion 76 to enclose the chamber formed by opening 64 and recess 62 and to shield terminal assembly 66 and the exposed terminations of dipoles 24 and wire 60 thereto, from the environment.

Plate 80 is provided with a hole 82 through which the end of screw 70 is adapted to project when segments 49, 50 are secured together and a plate 80 is seated on ledge 78. A cap nut 84 of insulating material is adapted to be threaded on the end of screw 70 to secure plate 80 to segment 50.

Segment 50 is preferably secured to segment 49 by means of suitable cement and by screws 86 passed through holes 88 and 90 respectively in segments 50 and 49 and nuts 92 threaded on the ends of screws 86. The ends of dipole elements 24 are also preferably cemented within channels 52 and 54 respectively of segments 49 and 50. The cementing of segments 49 and 50 together and of dipole elements 24 within channels 49 and 50 provides a water-tight and air tight-seal against the adverse effects of weather and environmental pollution.

The fan dipole assembly may be assembled as follows:

Plate 68 of terminal assembly 66 is cemented in recess 62 of segment 49 of bracket 43 and the ends of dipole elements 24 bared to expose conductors 75 which

are terminated to plate 68 by soldering. Segment 50 is then secured to segment 49 by cementing and by screws 86 and nuts 92 with the ends of dipole elements 24 cemented in channels 52 and 54 respectively of segments 49 and 50. Conductor 74 of wire 60 is then wound around screw 70 and trapped between nuts 72 threaded thereon after wire 60 is passed through the bore formed by channels 56 and 58.

Cover plate 80 is then seated on ledge 78 and cap nut 84 threaded on the end of screw 70 to secure plate 80 to segment 50.

A pair of fan dipole assemblies may be secured to boom 12 to form a fan dipole and simultaneously secured to mast 14 in the manner illustrated in FIGS. 2 and 3.

Although bracket 43 is shown as supporting three dipole elements it will be understood that any number of dipole or other antenna elements may be supported thereby. It will also be understood that bracket 43 may be made of any insulating material such as nylon or the like which may be formed into a rigid member.

Thus, it is seen that there is provided an antenna bracket according to the present invention which is resistant to corrosion and oxidation caused by adverse weather effects and environmental pollution. It may also be seen that there is provided a substantially watertight and air-tight electrical connection between the antenna elements supported by the bracket and a lead-in wire and that said antenna bracket is substantially maintenance-free over a long period of time and may be quickly assembled into an antenna assembly.

What is claimed is:

1. An antenna bracket comprising means for supporting at least one antenna element in a substantially air-and-water tight seal, said supporting means having an angled member of insulating material, said member having first and second legs, said first leg having a channel adapted to receive a portion of a support member to which the bracket is to be secured, said second leg having at least one bore adapted to receive an end of an antenna element, said second leg further having a chamber communicating with said bore and means for electrically connecting said at least one antenna element to a lead-in wire in such manner that said electrical connection is air-and water-tight, said electrical connecting means comprising a terminal assembly of conductive material positioned within said chamber, said terminal assembly being adapted to have said antenna element electrically connected thereto.

2. The antenna bracket of claim 1 wherein said supporting means is provided with means for receiving a portion of a support member to which the bracket is to be secured.

3. The antenna bracket of claim 2 wherein said supporting means comprises a member of insulating material and wherein said receiving means comprises a channel in said member adapted to receive a portion of a support member to which said bracket is to be secured.

4. The antenna bracket of claim 1 wherein said second leg has a second bore communicating with said chamber and adapted to receive the end of a lead-in wire and wherein said terminal assembly includes means for electrically connecting said lead-in wire thereto.

5. The antenna bracket of claim 1 wherein said second leg of said angled member comprises a first seg-

ment integral with said first leg and a second separable segment adapted to be secured to said first segment, and wherein said at least one antenna element receiving bore comprises complementary channels in opposing faces respectively of said first and second segments of said second leg.

6. The antenna bracket of claim 5 wherein said chamber in said second leg is comprised of a recess in said first segment of said second leg and an aperture in said second segment of said second leg aligned with 10 said recess when said segments are secured together.

7. The antenna bracket of claim 6 including a cover plate of insulating material adapted to be secured to said second segment of said second leg to cover said aperture therein.

8. The antenna bracket of claim 1 wherein said chamber in said second leg is comprised of a recess therein and including a cover plate of insulating material adapted to be secured to said second leg to cover said recess.

9. The antenna bracket of claim 1 wherein said terminal assembly comprises a plate adapted to be positioned in the bottom of said chamber and a screw integral with said plate and projecting substantially perpendicularly therefrom.

10. The antenna bracket of claim 9 wherein said second leg of said angled member has a second bore communicating with said chamber and adapted to receive the end of a lead-in wire and wherein said terminal assembly includes at least one nut threaded on said 30 screw, said end of said lead-in wire being adapted to be electrically connected to said assembly by trapping it between said nut and said plate.

11. The antenna bracket of claim 9 wherein said second leg of said angled member has a second bore communicating with said chamber and adapted to receive the end of a lead-in wire and wherein said terminal assembly includes a pair of nuts threaded on said screw, said nuts being adapted to electrically connect said 40 lead-in wire to said assembly by trapping an end thereof between said nuts.

12. An antenna assembly comprising means for supporting at least one antenna element in a substantially air- and water-tight seal, at least one antenna element having an outer surface which is substantially air- and water-tight supported by said supporting means, said supporting means having means for electrically connecting said at least one antenna element to a lead-in wire in such manner that said electrical connection is air- and water-tight, said supporting means comprising 50

an angled member of insulating material, said member having first and second legs, said first leg having a channel adapted to receive a portion of a support member to which the bracket is to be secured, said second leg having at least one bore, said at least one antenna element having an end secured in said bore in said second leg, in an air- and water-tight manner, said second leg further having a recess therein communicating with said bore and said electrically connecting means comprising a terminal assembly of conductive material positioned within said recess, said at least one antenna element being electrically connected to said terminal assembly.

13. The antenna assembly of claim 12 wherein said supporting means is provided with means for receiving a portion of a support member to which said assembly is to be secured.

14. The antenna assembly of claim 12 wherein said second leg has a further bore communicating with said recess and adapted to receive an end of a lead-in wire and wherein said terminal assembly comprises a plate, a screw projecting from said plate and a pair of nuts threaded on said screw, said nuts being adapted to terminate said lead-in wire to said assembly by trapping an end thereof between said nuts.

15. The antenna assembly of claim 14 including a cover plate of insulating material secured to said second leg overlying said recess.

16. The antenna assembly of claim 15 wherein said cover plate is provided with a bore, wherein said screw extends through said bore in said cover plate and including a cap nut of insulating material threaded on the end of said screw to secure said cover plate to said second leg.

17. The antenna assembly of claim 16 wherein said second leg comprises a first segment integral with said first leg and a second separable segment adapted to be secured to said first segment, wherein said bores in said second leg comprise complementary channels in opposing faces respectively of said first and second segments of said second leg and wherein said recess in said second leg comprises a recess in said first segment and an aperture in said second segment aligned with said recess in said first segment when said segments are secured together.

18. The antenna assembly of claim 12 wherein said antenna element comprises coaxial cable sheathed in fiberglass.
